(57) **CLAIM**

The ornamental design for a “water removing hair brush,” as shown and described.

DESCRIPTION

FIG. 1 is a front, right side, and bottom perspective view of my new design for a hair brush.

FIG. 2 is a front view of the hair brush shown in FIG. 1.

FIG. 3 is a rear view of the hair brush shown in FIG. 1.

FIG. 4 is right side view of the hair brush shown in FIG. 1, the left side view being a mirror image thereof.

FIG. 5 is a top view of the hair brush shown in FIG. 1.

FIG. 6 is a bottom view of the hair brush shown in FIG. 1; and,

FIG. 7 is a right side view of another embodiment of my new design for a hair brush, the hair brush having a modified bristle tip design, and the remaining views for the hair brush of FIG. 7 being the same as the views for the hair brush of FIGS. 1–6 but for the modified bristle tip design.

The broken lines shown represent unclaimed subject matter and form no part of the claimed design.
